8 Claims. (Cl. 178—44)

This invention relates to artificial lines for use on radio and other high frequencies and has for its object to provide improved variable artificial lines.

According to this invention an artificial line comprises an inductive coil arranged in association with a metal member in such manner that said metal member in conjunction with said coil provides the major portion of the effective distributed capacity of said coil and means are provided for varying the inductance per unit length of said coil and/or for varying the distributed capacity per unit length of said coil.

Artificial lines in accordance with this invention are applicable to a wide variety of uses and in order that the invention may be the better understood certain special uses to which said artificial lines may be put will be described.

In certain forms of radio apparatus, notably heterodyne receivers of the type wherein a very high intermediate frequency of the order of 2,000 kilocycles or more is employed, practical difficulties arise in obtaining a high impedance load in the anode circuit of valves, for example beat frequency valves. An important application of the present invention is to such apparatus wherein an artificial line is adapted for use as the anode impedance in circuit with a valve of a beat frequency amplifier operating at a high frequency of the order of 2,000 kilocycles or more. As will be appreciated, it is a matter of great convenience to be able to adjust the constants of an impedance employed for such a purpose as that described. Accordingly, for the purpose of exemplifying the utility of the invention, there will now be described two forms of artificial line, or impedance unit, either one of which may be employed as a variable impedance.

The invention is illustrated in the accompanying drawing in which,

Fig. 1 is a view, partly in section, of a coil construction which we preferably employ,

Fig. 2 is a transverse section with respect to the showing of Fig. 1,

Figs. 3 and 4 illustrate in elevation and transverse section respectively a modification of the invention,

Fig. 5 is a circuit diagram applicable to any of the embodiments herein shown; and

Fig. 6 shows a longitudinal section of still another embodiment.

Referring to Figures 1 and 2 which are respectively a side elevation partly in section and a transverse section of one form of construction, an artificial line comprises a coil 1 which may be

a simple solenoid, wound upon a cylindrical former 2 having radial projections 3 so that the wire of the coil is held away from the main body of the former. This former with its coil is positioned substantially concentrically within a split cylindrical copper screen 4 which is spaced a short distance radially from the coil and which has a split 4a running substantially parallel to the axis. The coil is positioned within the screen by suitable support members 5 which mechanically connect the body of the former with points in the screen diametrically opposite the split. Attached to the screen upon the outside thereof is a nut 6, this nut being positioned adjacent one side of the split 4a and approximately mid-way of the length of the screen. Also attached to the screen but upon the other side of the split and opposite the nut is an abutment member 7, for example of ebonite. The screen is of springy material and is sprung in such manner as to tend to close its split. Screwed through the nut is an adjustment screw 8 whose end bears in a suitable recess 7a formed in the abutment member. Thus it will be seen that by screwing the adjustment screw 8 in one direction the split 4a will be opened against the spring of the screen while by screwing the said screw in the other direction the spring of the screen will be allowed to close up the split to an extent limited by the setting of the said screw. The former 2 upon which the coil 1 is wound is a little longer than the screen and projects out at both ends thereof and over the projecting ends of the former are fitted annular end pieces 9, 10, for example of ebonite, these annular end pieces being embraced by short split cylindrical copper members 11, 12, each of which is closely held to its appropriate end piece by set screws 13 passing through the copper and screwing into the ebonite on the two sides of the split. It will be seen that with this arrangement movement of the adjustment screw in one direction or the other will change the effective distributed capacity of the coil since this capacity is largely constituted by the capacity between coil and screen.

The above described embodiment has the slight disadvantage that the coil is truly concentric with the screen for only one position of adjustment. This disadvantage may be obviated, if desired, by employing the modified embodiment now to be described and illustrated in sectional elevation and transverse section in Figures 3 and 4.

In this embodiment a coil 1 wound upon a former 2 and positioned within a split springy cylindrical screen 4 is employed as before but

a somewhat different method is utilised for opening and closing the split 4a in the screen. The former 2 upon which the coil 1 is wound is somewhat longer than the screen 4 and projects at both ends beyond the said screen. Upon one of the projecting ends is fixed an end piece 14, for example of ebonite, which embraces one projecting end of the former and has an outer face 14a of sloping form, the diameter of the end piece increasing rectilinearly outwardly of the former, as shown, i. e., as it approaches the extreme end of the former. The other projecting end of the former is screw threaded at 15 and over this end is fitted a somewhat similar end piece 16 which also has a sloping outer face 16a this end piece, however, being able to slide longitudinally with respect to the former. An ebonite ring nut 17 is screwed on to the threaded end 15 of the former outside the slidable end 20 piece. The copper screen has its ends turned up at 4b and bears at both ends upon the tapered faces 14a, 16a of the two end pieces 14, 16, as shown. With this arrangement when the ebonite nut 17 is screwed in one direction the two end pieces 14, 16 will be brought more close together and accordingly the split 4a in the screen will be compelled to open by reason of the fact that the turned up ends 4b of the screen bear upon the sloping faces 14a, 16a, of the end pieces 14, 16 25 and must accordingly ride up those sloping faces. Movement of the nut in the other direction allows the ends of the screen to come down the sloping faces and accordingly allows the split 4a to close to an extent determined by the setting 30 of the nut.

An artificial line in accordance with either of the specific embodiments just described, when adjusted to be a quarter of the working wave length long, may be used very satisfactorily as 40 a resonant anode impedance in the anode circuit of a beat frequency valve operating in a heterodyne receiver of the type wherein the beat frequency is very high, e. g., of the order of 2,000 kilocycles. The range of variation of the 45 effective distributed capacity of such an artificial line is sufficient to enable "trimming" adjustment to be made after the artificial line is connected in circuit. For example, as shown in Figure 5, an artificial line AL in accordance with 50 either of the embodiments hereinbefore described may have its coil 1 connected at one end directly to the anode A of the first detector or frequency changer valve FC of a heterodyne receiver, the other end of the coil being connected 55 to the screen 4 of the line and also to the source (not shown) of anode potential for the valve. Thus the artificial line constitutes a quarter wave length artificial line which is short circuited at one end.

60 Practical tests with artificial lines as above described have shown that a variation of 3% in the frequency at which the line is resonant is easily obtainable and such a range of variation is sufficient for "trimming" purposes, e. g., in the best 65 frequency amplifier of a heterodyne receiver.

It will, of course, be appreciated that when the 70 distributed capacity of an artificial line in accordance with either of the embodiments above described is varied, there is a change in the effective length of the line but this represents only a small percentage of the total length and in consequence the alteration in impedance resulting from such adjustment of distributed capacity 75 is too small to have any important effect upon

the valve stage in whose circuit the line is connected.

In a further embodiment in accordance with this invention and illustrated in longitudinal section in Figure 6 provision is made for varying both the distributed capacity and the inductance per unit length, this variation being effected in such manner that the inductance per unit length and capacity per unit length maintain a constant ratio towards one another. A variable artificial line in which the distributed inductance and capacity remain in a predetermined ratio towards one another, is useful for a variety of different purposes; for example, it may be used as a phase changing device in connection with a transmission circuit between an antenna and a remotely situated transmitter or receiver.

In the use of long transmission lines a phase changing device is oftentimes required to introduce a certain desired change of phase and since the amount of phase change introduced will obviously depend upon frequency, the phase changing device must be variable for tuning purposes. Such a variable phase changing device can, of course, be constituted by filters having reactances arranged to be varied together in such manner that for all positions of adjustment the phase changing device presents constant impedance, but such filters, with their necessary gang controlled reactances, are somewhat complicated. The present invention may be utilised to provide an improved simplified phase changing device wherein the phase shift may be varied while maintaining constant the characteristic of the impedance.

In the embodiment of the present invention illustrated in Figure 6 and suitable for use for purposes as just described, a variable artificial line construction comprises a cylindrical supporting tube 18 of insulating material held between end cheeks 19, 20. Enclosed in the tube, and extending over about half its length, is a cylindrical core 21, for example of the material known under the registered trade name "Ferrocarr". Concentrically surrounding the tube and core and of the same length as the core, is a cylinder 22 of dielectric material, for example glass, slightly spaced from the supporting tube 18 and attached to one of the end cheeks (cheek 20). Mounted upon the supporting tube 18 is a thin tube 23 of insulating material carrying a single layer helix 1 which can slide between the supporting tube 18 and the cylinder 22 of dielectric. This tube 23 carries at the end remote from the end cheek 20 a spacing ring 24 of insulating material round the outer edge of which is attached a copper cylinder 25, also of almost the same length as the core. The copper cylinder has a thin slit (which does not appear in the view of Figure 6) cut along its length to prevent its acting as a short circuited turn with respect to the solenoid 1. The radial thickness of the spacing ring 24 is such that the copper cylinder 25 can slide over the glass tube 22. The dielectric 22 therefore is interposed between the helix 1 and the copper cylinder 25 the arrangement thus constituting a variable capacity.

It will be seen that with this arrangement 70 when the copper cylinder and coil are moved in the direction of the end cheek 20 the effective inductance of the coil is increased since more of the ferro-magnetic core comes within the coil and at the same time the effective distributed 75

capacity of the coil is also increased in like ratio since more of the dielectric cylinder comes outside the coil. The whole arrangement is preferably (as shown) such that when the copper cylinder is moved to its maximum extent away from the end cheek 20 there is no core material inside the coil and no solid dielectric material outside the coil. With this construction by moving the slider the phase shift effected by the 10 artificial line when used as a variable phase changing device may be varied while maintaining constant the characteristic impedance since variation of inductance per unit length and variation of capacity per unit length takes place 15 at the same rate.

The input terminals are constituted by one end of the coil and the copper cylinder and the output terminals are similarly constituted by the other end of said coil and the said copper cylinder.

20 The expedient of varying distributed capacity by varying the amount of dielectric in association with a coil may be adopted in artificial lines in accordance with this invention wherein variation of distributed capacity is all that is required; 25 in other words, the first two specific embodiments hereinbefore described may be modified by substituting for the expedient of varying distributed capacity by varying the space between a coil and a screening member, the expedient of 30 varying the distributed capacity by varying a dielectric which in effect forms part of the distributed capacity. Similarly in artificial lines in accordance with this invention wherein variation both of inductance and capacity is required, the expedient adopted in the first two 35 embodiments specifically described herein may be employed for varying the distributed capacity.

It has been found in practice that, to obtain maximum effectiveness of artificial lines in accordance with this invention, the capacity between turns of the coil should be less than the capacity of each turn to the screen and if the inter-turn capacity is allowed to be larger than the turn-screen capacity the effectiveness of the 40 line is apt to be much reduced. For lines which are to have a low value of distributed inductance there are no difficulties in the way of obtaining a sufficiently high ratio of distributed capacity to inter-turn capacity since the number of turns per 45 unit length will be low. Where, however, higher values of distributed inductance are required, i. e., where the design calls for a relatively large number of turns per unit length, the use of coils wound in the ordinary way with round sectioned 50 wire may not be as satisfactory as is desired since it may result in the inter-turn capacity exceeding the turn-screen capacity. In such cases, therefore, it is preferred to wind the coil with flat strip with its flat face presented to the screen 55 so that the inter-turn capacity is due to the capacity between adjacent narrow edges of the strip winding while the wide face of the strip co-operates with the screen to provide the turn 60 screen capacity.

65 We claim:

1. An artificial line comprising a cylindrical coil, a split cylindrical screen substantially surrounding said coil and in electrostatic association with the same, and means for widening or reducing said split so as to vary the distributed capacity due to said screen, said line being further characterized in that the screen is of springy material and has the split parallel to the coil axis, said screen being fixed relative to said coil 70 axis, at a point or points opposite said split, the means 75

for varying the width of said split comprising a screen member bridging said split and adapted to force said split to widen against the springiness of the screen.

2. An artificial line comprising a cylindrical coil, a split cylindrical screen substantially surrounding said coil and in electrostatic association with the same, and means for widening or reducing said split so as to vary the distributed capacity due to said screen, said line being further characterized in that the screen is of springy material and has the split parallel to the coil axis, means including end-supporting members for positioning said screen, said means having oppositely tapered faces, one of said end members being fixed on said coil structure and the other being longitudinally movable so that by bringing said end members nearer to one another said screen may be forced to ride up on said tapered faces thereby to widen its split 20 against the springiness of said screen.

3. An artificial line comprising a tubular guide member, a ferro-magnetic core co-axial with and inserted into one end of said guide member and extending over a fraction of the length thereof, a tubular dielectric member of insulating material also co-axial with said guide member and surrounding the same over a length substantially corresponding to the length of insertion of said core, and a coil structure consisting of a 30 tubular coil having a spaced metal screen carried from one end thereof and co-axially surrounding said coil, said coil structure being of approximately the same length as the length of said core insertion and being slidably mounted 35 on said guide, the whole arrangement being such that by moving the coil structure towards the end of the guide member where the core is inserted said coil will pass inside and said screen outside said tubular dielectric member both inductance and capacity being thus simultaneously variable.

4. A line as claimed in claim 3 and wherein the arrangement is such that the inductance of the coil and the effective distributed capacity 40 thereof may be variably adjusted in like ratio by moving the coil structure along the guide member.

5. An impedance unit comprising a conductive helical coil, a magnetic core member within said coil, a split cylindrical metallic shielding member closely adjacent and substantially surrounding said coil, and providing a greater capacitive reactance with respect to the convolutions of said coil than the total distributed capacitance of 55 the coil itself, and means for simultaneously adjusting the relative positions of the shielding member and of the coil with respect to said core member, thereby to vary the effective over-all 60 capacitance of the impedance unit, while maintaining a predetermined ratio between the distributed inductance and the distributed capacitance of said unit.

6. An impedance unit according to claim 5 and having said helical coil constituted by a single layer of flat wire, the edges of which are in juxtaposition while one broad face thereof is opposed to said shielding member.

7. An impedance unit comprising a stationary 70 magnetic core member, an insulating sleeve surrounding said core member and of greater axial length than said core member, a conductive helix surrounding said sleeve and adjustably positionable thereon, a split metallic shielding member 75

substantially surrounding said helix and insulated therefrom while being mounted integrally therewith, and means including a sleeve of dielectric material mounted in fixed relation to said core member and insertible between said helix and said shielding member for determining the capacitance between said helix and said shielding member.

8. An impedance unit in accordance with claim 7 and having the dimensions of the several parts

so fixed in relation to one another that variations in the position of said helix and shielding member relative to said magnetic core and dielectric sleeve respectively result in a phase shift effect upon the circuit in which said unit is connected, while maintaining constant the impedance characteristic of said unit.

JOSEPH DOUGLAS BRAILSFORD.
